UNITED STATES PATENT OFFICE

HORACE H. PEEK, OF CHATTANOOGA, TENNESSEE

SECTIONAL HEATING BOILER

Application filed February 24, 1928. Serial No. 256,543.

This invention relates to heating boilers and includes all improvements over the prior art which are disclosed in this application.

Broadly, one object is to improve the construction disclosed in my application on sectional heating boiler, Serial No. 30,990, filed May 18, 1925.

Specifically, one object is to improve the construction of the gas or smoke passages and door and other large openings in the sections of the boiler, by providing a more homogeneous and proper thickness of metal, particularly at the corners.

Another object is to provide a stronger 15 joint and prevent leaks where the nipples connect the sections together.

Another object is to provide a stronger outlet with less chance of leakage.

Another object is to increase the heating 20 surface and therefore steam generation surface and provide better water circulation, by forming the sections so that the ash pit is completely surrounded by water. This construction also provides a settling chamber for 25 any mud or sediment that may be in the water.

Another object is to provide for easy cleaning of the bottoms of the horizontal water chambers of the sections.

The above and other objects which will 30 hereinafter appear, are attained by the new and useful improvements disclosed in this application. To enable others skilled in the art to fully understand the essential characteristics of the improvements, drawings illustrating one mode of carrying out the invention have been annexed as part of this disclosure.

Fig. 1 is a longitudinal sectional view of the boiler on line 1—1 of Fig. 2 with the doors 40 omitted.

Fig. 2 is a top plan view of the boiler with one half shown in section on line 2—2 of Fig. 1.

Fig. 3 is a front elevation of the boiler showing doors and dampers thereon.

Fig. 4 is a section on line 4—4 of Fig. 1.

Figs. 5, 6, 7, 8, 9 are front elevations respectively, of the left halves of symmetrical 50 units 1, 2, 3, 4, 5.

Figs. 10, 11, 12, 13, 14, are sections of Figs. 5, 6, 7, 8, 9 respectively on line 10—14.

Figs. 15, 16, 17, 18, 19, are sections of Figs. 5, 6, 7, 8, 9, respectively, on line 15—19.

Figs. 20, 21, 22, 23, 24, are sections of Figs. 5, 6, 7, 8, 9, respectively, on line 20—24.

Figs. 25, 26, 27, 28, 29, are sections of Figs. 5, 6, 7, 8, 9, respectively on line 25—29.

Fig. 30 is an enlarged view of the reinforced plate construction, where a nipple connects two sections as shown in Fig. 1.

The present embodiment of boiler is broadly similar to that in my previously referred to application Serial No. 30,990, except in such respects as are different in the drawings of the present application. The boiler includes a water container including a plurality of units or sections 1, 2, 3, 4, 5, bolted together by thru rods 6 in a usual manner. Unit 1, for example, (Figs. 1, 2, 3, 5, 10, 15, 20, 25) is made by pressing to shape complementary parts 10, 11 of sheet metal, preferably steel, and integrally joining the same preferably edge to edge along their meeting edges preferably by autogenous welding such as by gas or the electric arc as indicated at 12.

In the gas or smoke and door openings 13, in units 1, 2, 3, 4, 5, the edges of the complementary parts 10, 11 do not meet, but the edges 14 are turned or flanged slightly inward toward each other, and a thimble 15 is made of a suitable size to fit within the opening. Any or all of the thimbles may be seamless as at 16 or formed by bending to shape from a piece of sheet metal and welding the meeting edges together as at 17. Whichever way the thimble is formed, it is placed within an opening 13 and its edges are expanded to have a flare, and welded as at 18. This makes a water tight construction with the metal homogeneous and of normal full thickness at the corners.

In the case of the larger openings in units 2, 3, 4, 5 those corners where the metal would be subjected to maximum thinning if made integral, are made by inserting corner pieces 19 and welding each of them along its four edges as at 20, thus providing full thickness of metal at the corners and making a more perfect boiler.

Reinforcing plates 21 (Fig. 30) are welded on the inside of the section walls at the places where nipples 22 connect the sections together. This gives a stiffer and stronger construction and increases the bearing surface for the slip or screw nipple, thereby providing a tighter joint and preventing leaks around the connection nipple where the sections are connected together.

10 Each of outlets 23 is welded on the outside at 24, and on the inside has a flange 25 which may also be welded at 26. The welding on the outside with flange inside gives a strong watertight construction, and when the flange inside is also welded, still greater strength is obtained with minimum chance of leakage.

The sections preferably all extend down to the bottom of the boiler and have bottom horizontal water chambers 27, thus completely surrounding the ash pit. This construction provides additional heating surface and therefore additional steam generation surface. It also increases the rapidity of the circulation of the water in the boiler, and 25 also provides a settling chamber for catching the mud or sediment that may be in the water used in the boiler.

Openings 28 on opposite sides of the sections are normally closed by removable plugs 29, and are so placed preferably to permit cleaning in a line in the direction of width of the sections and just above the bottoms of the various horizontal water chambers 27, 30. This provides means for readily cleaning 35 the boiler free of mud or scale by means of a bar or hose inserted and operated through openings 28.

The invention may be embodied in other specific forms without departing from the spirit or essential characteristics of the invention, and the present embodiment is therefore to be considered in all respects as illustrative and not restrictive, the scope of the invention being indicated by the appended 45 claims rather than by the foregoing description, and all changes which come within the meaning and range of equivalency of the claims are therefore intended to be embraced therein.

50 I claim:

1. A sectional boiler section including, two pressed to shape sheet metal complementary parts having edges extending toward each other and welded together to partially form 55 an opening in the section, and a number of corners of the opening each formed by an inserted corner piece extending across the line of weld of the edges of the complementary parts, and the edges of said inserted corner piece being welded to said complementary parts.

2. A sectional boiler section including, two pressed to shape sheet metal complementary parts having outer edges extending toward 60 each other and welded together, and a smoke

or door opening partially formed by edges of the complementary parts around the opening extending toward each other, and a thimble in the opening having its edges welded to the complementary parts around the opening.

3. A sectional heating boiler including, a plurality of sections connected together, a grate and an ash pit, a majority of the sections in the region of the ash pit having 75 water chambers extending across beneath the ash pit and having the lower walls of said chambers substantially straight and free from projections for direct engagement with a supporting floor.

In testimony whereof I hereunto affix my signature.

HORACE H. PEEK.
